US0D1113919S

(12) **United States Design Patent** (10) **Patent No.:** **US D1,113,919 S**
(45) **Date of Patent:** **** Feb. 17, 2026**

(54) **HOUSING OF SATELLITE SIGNAL RECEIVER**

(71) Applicant: **SCAN2CAD INC.**, St Petersburg, FL (US)

(72) Inventor: **Yashuai Huang**, Shanghai (CN)

(73) Assignee: **SCAN2CAD INC.**, St Petersburg, FL (US)

(**) Term: **15 Years**

(21) Appl. No.: **29/997,691**

(22) Filed: **Apr. 9, 2025**

(30) **Foreign Application Priority Data**

Aug. 30, 2024 (CN) 202430553472.4

(51) **LOC (15) Cl.** **14-03**

CLAIM

The ornamental design for a housing of satellite signal receiver as shown and described.

DESCRIPTION

FIG. 1 is a front perspective view of a housing of satellite signal receiver according to our new design.

FIG. 2 is a bottom perspective view thereof;

FIG. 3 is a front view thereof;

FIG. 4 is a rear side view thereof;

FIG. 5 is a left side view thereof;

FIG. 6 is a right side view thereof;

FIG. 7 is a top view thereof; and,

FIG. 8 is a bottom view thereof.

The broken lines illustrate portions of the housing of satellite signal receiver that form no part of the claimed design.

1 Claim, 8 Drawing Sheets
